Inventor;

UNITED STATES PATENT OFFICE.

J. S. DAVISON, OF CRANBERRY, NEW JERSEY.

IMPROVED TELEGRAPHIC CABLE.

Specification forming part of Letters Patent No. 25,562, dated September 27, 1859.

To all whom it may concern:

Be it known that I, J. S. DAVISON, of Cranberry, in the county of Middlesex and State of New Jersey, have invented a new and Improved Telegraph-Cable; and I do hereby declare that the following is a full, clear, and exact description of the same, reference being had to the accompanying drawings, forming a part of this specification, in which—

Figure 1 represents a sectional elevation of my invention. Fig. 2 is a transverse vertical section of same.

Similar letters of reference in both views indicate corresponding parts.

Telegraph-cables which, when they are submerged in deep water, are subjected to a certain strain have to be so arranged that the conductor is fully protected against all injurious influences of this strain. A straight wire stretched from end to end surrounded by a coil and by the insulating substance will certainly break when the cable is submerged, for a comparatively small strain will cause the coil to stretch, and the conducting-wire, together with the insulating substance, has to support the whole weight of that portion of the cable which may be suspended between the surface and the bottom of the water. The conductor must either be protected in such a manner that said protection is able to withstand the strain without being stretched, or, if the protection stretches, the conductor must be so constructed that it can stretch also without being injured.

With my cable the conductor is protected by a coil, which, of course, will stretch if it is subjected to a strain, and the conductor itself consists of a series of loose strips of copper wire that are hooked on or otherwise united to the coil and which fill up the space in the inside of the coil, so that when the coil stretches

each of said strips assumes a longitudinal sliding motion, and as the coil by being stretched diminishes its diameter said strips are brought close together and the current passes through without interruption.

To enable those skilled in the art to make and use my invention, I will proceed to describe it.

A represents a coil of copper wire or of any other suitable metal. Iron may be used, if desired, as the coil is not used as a conductor. This coil is surrounded by an insulating-tube, B, and its interior is filled up by a series of loose strips of copper wire, a. Each strip may be made of any desirable length, and each of them is fastened to the coil with one end by means of hooks b or in any other convenient manner. When the coil stretches each strip assumes a longitudinal sliding motion, and as the diameter of the coil diminishes when the same is stretched the loose strips are brought closer in contact, and the current passes through without interruption. These loose strips ought to be made of copper wire or silver wire, as it is desirable that the conductor of the cable offers as little resistance as possible to the electric current. It is also desirable to keep the surface of the conducting-wires bright, whereby the current will be enabled to pass with more ease from one wire to the other.

Having thus fully described my invention, what I claim as new, and desire to secure by Letters Patent, is—

Arranging a series of loose metal strips, a, in a coil, A, or its equivalent, substantially as and for the purpose described.

J. S. DAVISON.
